UNITED STATES PATENT OFFICE.

ALBERT MOYER, OF NEW YORK, N. Y.

MIXER.

Application filed June 12, 1928. Serial No. 284,866

This invention relates to mixers particularly adapted for use in mixing the ingredients of concrete.

At the present time there is a tendency in concrete practice to use a stiff mix and the mixers now available are not adapted to handle or effect the thorough intermixing of the relatively dry ingredients of a stiff mix of concrete.

10 This invention has for its salient object to provide a mixer so constructed and arranged that relatively stiff or dry mixtures of materials will be thoroughly agitated and intermixed therein.

15 Further objects of the invention will appear from the following specification taken in connection with the drawings, which form a part of this application, and in which

Fig. 1 is a sectional elevation of a mixer 20 constructed in accordance with the invention;

Fig. 2 is an end elevation, partly in section, of one end of the mixer shown in Fig. 1;

Fig. 3 is a detail sectional elevation showing a slightly modified form of driving connection for reciprocating the shaft in the mixer; and

Fig. 4 is a view similar to Fig. 3 but illustrating another form of driving connection.

30 The invention briefly described consists of a mixer comprising a rotary drum having a shaft disposed therein provided with agitating or stirring blades or paddles. The drum is operatively connected to driving connections whereby the drum can be rotated in one direction and driving connections are also provided for rotating the shaft in a direction opposite to the direction of rotation of the drum. In order to effect a thorough agitation and intermixing of the ingredients in the drum, the shaft is reciprocated during its rotation, thus causing the stirrers or paddles to move longitudinally of the drum axis as well as in a rotary path.

45 Further details of the invention will appear from the following description.

In the form of the invention shown in Fig. 1, the drum 10 has secured to the outer surface thereof, annular bands 11 and 12 having flanges 13 and 14. The drum is mounted on two sets of rollers 15 and 16 which engage the bands 11 and 12. The rollers are carried by uprights 18 and 19 mounted on a base 20. One set of rollers is mounted on a shaft 25 55 supported in bearings 26 and 27 and driven

from any suitable source of power. The drum 10 has secured to the inner surface thereof, a plurality of baffles or deflecting members 29.

The drum has a gear 30 secured to the outer surface thereof which is driven by a gear 31 mounted on shafts 25.

A hollow shaft 35 is rotatably and slidably mounted in hubs 36 formed on or secured to the drum 10. The shaft 35 is splined as shown at 37' to a shaft 37 slidably mounted in the shaft 35 and driven by a sprocket and chain connection 38, 39 and 40 from the shaft 25. It will be obvious that the shaft 37 is driven in a direction opposite to the direction of drive of the drum 10.

The hollow shaft 35 has secured thereto a plurality of radially extending arms 45 on which are mounted paddles or blades 46 for agitating and mixing the ingredients in the drum.

In addition to being rotated, the shaft 35 is also reciprocated back and forth in the drum. In the form of the invention illustrated in Fig. 1, this is accomplished by means of a bell crank lever pivoted at 50 to an upright 51. One arm 52 of the bell crank lever has the end 53 thereof disposed in a cam groove 54 of a cam 55 mounted on the shaft 25. The cam groove is eccentric to the axis of rotation of the shaft 25 and causes the arm 52 and the bell crank lever to oscillate back and forth on the pivot 50 during the rotation of the cam.

The other arm 52' of the bell crank lever is connected to a link 56 having a ball 57 on the free end thereof. The ball 57 is disposed in a spherical socket 58 of a block 59 secured in one end of the hollow shaft 35.

It will be clear from the foregoing description that as the shaft 25 is rotated, the cam 55 will oscillate the bell crank lever, thus imparting a reciprocatory movement to the hollow shaft 35. The shaft will, however, be rotated simultaneously with its rotation by means of the splined connection 36 with the shaft 37.

The material to be mixed is introduced into the receptacle 10 through an opening therein normally closed by a door or removable plate 60.

In the form of the invention illustrated in Fig. 3, the link 66 which corresponds to the link 56 shown in Fig. 1 is connected to an arm 67. The lower end of the arm 67 has

secured thereto a nut or block 68 which is disposed in a groove 69 of a cylindrical cam 70. The cam 70 has right and left hand spiral threads therein and as the cam is rotated the nut 68 will follow the spiral grooves or threads and will cause the arm 70 to be reciprocated back and forth. Any suitable guiding means may be provided for guiding the arm 67 during its reciprocation.

- 10 Fig. 4 illustrates another form of driving connection for reciprocating the hollow shaft 35. In this form of the invention a fixed cam 75 is mounted in the end of the shaft 35. The cam 75 has a double spiral groove therein having right and left hand threads and the shaft has secured thereto and extending inwardly therefrom into the cam groove, a lug or nut 76. A disk 77 is secured to one end of the cam 75 for centering the cam in the hollow shaft. Since the cam 75 is held against turning, the rotation of the shaft 35 will cause the nut or lug 76 to follow the spiral grooves in the cam and to cause the reciprocation of the hollow shaft 35.
- 15 25 From the foregoing description it will be evident that simple and practical driving connections have been provided for a mixer of the type specified and by means of the connections defined, the drum will be rotated in one direction and the centrally disposed member or hollow shaft will be rotated in the opposite direction. Furthermore, the hollow shaft will be reciprocated during its rotation, thus causing the paddles or blades 30 to reciprocate back and forth in the receptacle as well as to rotate therein. Due to the reciprocatory and rotary motion of the blades, an efficient and thorough agitation and intermixing of the material will be obtained.

20 35 40 Although certain specific embodiments of the invention have been particularly shown and described, and several different forms of driving connections have been set forth, it will be obvious that changes in the construction and in the arrangement of the various cooperating parts and in the driving connections may be made without departing from

the spirit or scope of the invention, as expressed in the following claims.

50

What I claim is:

1. A mixer comprising a rotatable receptacle, a rotatable member extending into the receptacle, stirrers mounted on said member, and means for shifting said rotatable member axially during its rotation.

2. A mixer comprising a rotatable receptacle, a rotatable member extending into the receptacle, stirrers mounted on said member, and means for reciprocating said rotatable member axially during its rotation.

3. A mixer comprising a rotatable receptacle, a rotatable member extending into the receptacle, stirrers mounted on said member, and means for reciprocating said rotatable member axially during its rotation in one direction.

4. A mixer comprising a rotatable receptacle, a rotatable member extending into the receptacle, stirrers mounted on said member, and means including a cam and operative connections actuated thereby for shifting said rotatable member axially during its rotation.

5. A mixer comprising a rotatable drum, a shaft extending axially through said drum, stirring devices carried by the shaft, means for rotating the drum, means for rotating the shaft, and means for shifting the shaft axially during the rotation thereof.

6. A mixer comprising a rotatable drum, a shaft extending axially through said drum, stirring devices carried by the shaft, means for rotating the drum in one direction, means for rotating the shaft in the opposite direction, and means for shifting the shaft axially during the rotation thereof.

7. A mixer comprising a rotatable drum, a shaft extending axially through said drum, stirring devices carried by the shaft, means for rotating the drum in one direction, means for rotating the shaft in the opposite direction, and means for reciprocating the shaft axially during the rotation thereof.

In witness whereof, I have hereunto set my hand this 4th day of June, 1928.

ALBERT MOYER.
